EDWARD A. JOHNSTON AND CHARLES I. LONGENECKER, OF CHICAGO, ILLINOIS,
ASSIGNEES TO INTERNATIONAL HARVESTER COMPANY, A CORPORATION OF
NEW JERSEY.

INTERNAL-COMBUSTION ENGINE.

1,129,099.

Specification of Letters Patent. Patented Feb. 23, 1915.

Application filed February 13, 1911. Serial No. 606,398.

To all whom it may concern:

Be it known that we, EDWARD A. JOHNSTON and CHARLES I. LONGENECKER, citizens of the United States, residing at Chicago, in the county of Cook and State of Illinois, have invented certain new and useful Improvements in Internal-Combustion Engines, of which the following is a specification.

10 Our invention relates to internal combustion engines, and in particular to a method of automatically controlling the temperature within the cylinder and combustion chamber whereby any excess heat is rapidly dissipated and carried away intermittently by successive discharges of volumes of steam and hot water from the water jacket surrounding the cylinder and combustion chamber, followed by an inflow of 15 colder water thereto, the frequency of discharge depending upon the load upon the engine and consequent change in volume of the explosive mixture consumed.

Our invention may be practised by means 25 of the mechanism illustrated in the accompanying drawings, in which—

Figure 1 represents a side elevation of an internal combustion engine designed to operate in accordance with our method; Fig. 30 2 is an end elevation of Fig. 1; and Fig. 3 is a fragmentary view in section of part of the water supply means connected with the water chamber of the cylinder.

The same reference characters designate 35 like parts throughout the several views.

1 represents a base frame, upon which is mounted an engine frame 2, having a crank shaft 3 journaled at one end thereof and a power cylinder 4 secured at its opposite end. 40 The cylinder is surrounded by an annular water receiving chamber 5 common to the class of engines indicated, and is provided with an intake valve 6 opening into the combustion chamber and communicating with 45 a carburetor mechanism 7.

8 indicates a casing surrounding a centrally arranged conduit 9 forming part of the carburetor, the casing having a chamber for the reception of water.

50 10 indicates a water supply pipe leading to the chamber, and 11 an overflow pipe leading therefrom.

12 represents the exhaust valve mechanism, and 13 the exhaust pipe leading therefrom.

14 represents a cooling water supply tank carried by the base frame and adapted to contain a body of water in its lower portion and having its upper portion open to the atmosphere and provided with a spray pipe 60 15 across its upper end.

16 represents a water circulating pump mounted upon a bracket 17 secured to the engine frame, having a plunger 18 connected by means of a pitman 19 with an eccentric 20 secured to the engine shaft, and a valve chamber 21, the valve chamber being connected with the lower part of the water supply tank by an inflow pipe 22 and with the upper end of a condenser 23, located 70 above the water tank, the valve chamber being connected with the condenser by means of an outflow pipe 24, the lower end of the condenser being connected with the spray pipe 15 by means of a curved pipe 25. 75

26 represents a feed pipe connected with the outflow pipe leading from the pump below its connection with the condenser and leading to the pipe 10 connected with the water chamber of the carburetor mechanism 80 and supplying a continuous flow of water thereto.

27 represents an eduction pipe having one end communicating with the water chamber surrounding the cylinder intermediate 85 its length, and its opposite end with the condenser below the connection of the outflow pipe from the water pump therewith.

28 represents a constant level gravity feed 90 water cup at one side of the engine cylinder and having its lower end communicating with the water chamber surrounding the said cylinder by means of a duct 29, and 30 represents a check valve in the duct that 95 closes against the water pressure in the cylinder.

31 represents an overflow pipe leading from near the upper end of the cup to the bottom of the water supply tank and provided with a check valve 32 that closes 100 against the tank. The upper part of the cup 28 is approximately in the same horizontal plane as the upper wall of the power cylinder, and the duct 29 communicates 105 with the water chamber below the upper level thereof.

When using heavy liquid fuel, as kerosene, in the operation of engines of the type indicated, it is necessary to have a higher 110

temperature in the cylinder and combustion chamber in order that the oil may be properly vaporized, and not subsequently condense, than with the use of a lighter hydrocarbon, such as gasoline, and it is necessary to provide means whereby the temperature may be controlled at a substantially constant value even under varying engine load conditions and in spite of accompanying variations in the quantity of fuel burned. It is a common practice to provide means for producing a forced continuous circulation of water from a source of supply through the water chamber surrounding the engine cylinder and so regulating the flow that a desired temperature condition in the walls of the cylinder is approximately maintained when the engine is working under full load, and a maximum of fuel is being consumed; but with apparatus so adjusted and operating the wall temperature is very materially lowered when the engine is relieved of load and is consuming its minimum quantity of fuel, and soon reaches a point that is not sufficiently high for effective vaporization of the hydrocarbon or the prevention of condensation of fuel previously vaporized. To restore proper operative conditions the supply of cooling water must be reduced in order to meet the changed conditions of heat supply. Various means have been provided by others for regulating the flow of water, all more or less dependent upon the care and watchfulness of the operator.

We have discovered a method of accomplishing the desired result of automatically controlling the flow of the water so as to remove heat from the walls approximately in proportion to the rate at which they receive heat as varying amounts of explosive mixture are burned and so establishing and automatically maintaining a reasonably constant temperature condition of the walls of the combustion chamber at all engine loads. Our method consists in a particular mode of admitting water to and discharging it, together with some steam, from the jacket that we have found suitable for the purpose and that depends on certain properties of steam and water. A body of water, if locally heated, may remain comparatively cool at other points and, in fact, by reason of its slow heat conducting power may have steam pockets near the localized heat supply while other parts are quite cool. The water in a gas engine cylinder and head jacket is heated unequally, the supply of heat from the fuel in combustion to the water being mainly concentrated near the cylinder head or to the surrounding and containing walls of what is commonly known as the combustion chamber. Accordingly such a jacket may have water boiling near the head end and be compara-

tively cool at the crank end with warm water of varying degrees between. We utilize the pressure of the steam thus formed to discharge some of the hot water through a suitably located outlet, which also serves as a steam pressure relief, and we utilize the reduced level of water in the jacket that results from the discharge of hot water and steam to resupply an equivalent amount of cooler water in conjunction with a constant level supply cup at the side of the cylinder. This inflow of cool water is followed by steam generation, producing pressure to discharge hot water and steam until the pressure is relieved and the level lowered in the jacket, and this, in turn, by an inflow of more cool water. Inflow of cool water and discharge of hot water and steam occur in succession and intermittently and as fast as the heat supply is able to make steam, but as no discharge takes place until steam forms, the combustion chamber walls are periodically and at short but properly proportionate periods brought up to steam temperature, which, being constant, keeps the walls at substantially constant temperature. When the engine is first started the temperature within the cylinder being comparatively low, the water flowing from the constant level cup having its overflow outlet approximately in the same horizontal plane as the upper level of the water chamber, will fill the chamber to the same level; but following the first discharge of steam and water therefrom, a volume of steam collects in the upper level that has sufficient pressure to hold back the inflow of water, leaving more or less of the chamber unoccupied by water, depending upon the frequency of discharge and pressure of the steam.

What we claim as our invention, and desire to secure by Letters Patent, is:

1. In an internal combustion engine having a power cylinder and a cooling water chamber surrounding said cylinder, the method which consists in intermittently admitting to said power cylinder charges of exploding mixture, successively exploding said charges in said cylinder, thereby liberating heat to the walls of the cylinder, then absorbing this liberated heat by water in the water chamber until some of the water is changed to steam, then intermittently discharging hot water and steam from the water chamber by expansion of the steam, and intermittently admitting colder water to take the place of the hot water and steam discharged for automatically holding said walls at a temperature suitable for efficient combustion of the fuel, the frequency of this intermittent interchange being governed automatically by the quantity of heat liberated by the fuel consumed.

2. The method of maintaining substan-

tially constant the temperature of the cylinder walls of an operating internal combustion engine having a cooling chamber adjacent the cylinder, consisting in filling 5 the chamber with a cold liquid, absorbing heat liberated by the engine by the cold liquid until some of the liquid in said chamber is changed into a gas or vapor thereby generating a pressure in said chamber, in- 10termittently driving part of the remaining liquid from said chamber by the gas or vapor pressure so generated, and supply- 15ing intermittently cold liquid to take the place of the liquid thus driven out of the chamber.

3. The method of maintaining substan-

tially constant the temperature of the cylinder walls of an operating internal combustion engine having a cooling water chamber, consisting in absorption of heat 20 liberated by the engine by water in said chamber until some of the water is changed to steam, then intermittent expulsion of water from the chamber caused by the ex- 25pansion of said generated steam in said chamber, and intermittent induction of wa- ter to take the place of the water expelled.
